UNITED STATES PATENT OFFICE.

JOHN H. GOSS AND ADRIAN F. WOLFF, OF WATERBURY, CONNECTICUT,
ASSIGNORS TO SCOVILL MANUFACTURING COMPANY, OF WATERBURY,
CONNECTICUT, A CORPORATION OF CONNECTICUT.

BOX FOR WATCH-MOVEMENTS.

No. 853,236.

Specification of Letters Patent.

Patented May 14, 1907.

Application filed May 31, 1906. Serial No. 319,506.

To all whom it may concern:

Be it known that we, JOHN H. GOSS and ADRIAN F. WOLFF, citizens of the United States, residing at Waterbury, in the county of New Haven and State of Connecticut, have invented a certain new and useful Improvement in Boxes for Watch-Movements, of which the following is a full, clear, and exact description.

The object of this invention is to provide a metal receptacle for the transportation and handling of watch movements before they are put in their cases.

Numerous devices of this same general character have been heretofore patented and used, and in this aspect the present invention is in the nature of an improvement.

The invention consists of a movement box having telescoping portions provided with inserted ends, a rest and a spring seat or clamp for engaging a projecting portion, flange or plate on the watch movement to hold the movement in a cushioned manner within the box.

The invention also includes means for holding the inserted ends in the box, all as we will proceed now more particularly to set forth and finally claim.

In the accompanying drawings, illustrating the invention, in the several figures of which like parts are similarly designated, Figure 1 is a transverse section, greatly enlarged, of the glazed movement box detached. Fig. 2 is a side elevation. Fig. 3 is a section like Fig. 1 but on a smaller scale, and showing the watch movement in position therein. Fig. 4 is a plan view of the spring. Fig. 5 is an elevation of the spring. Fig. 6 is a cross-section of the casing showing the movement box therein in elevation. Fig. 7 is a plan view of the bottom of the casing. Fig. 8 is an inverted plan view of the top of the casing.

The movement box comprises a cylindrical shell 1 having its upper edge provided with an inturned flange 2 which forms a rest for some projecting portion or plate or other member 3 of the watch movement 4, the body of which is suspended from said flange 2 within the cylindrical shell 1, has an opening for the insertion of a transparent or other plate, and as indicated in Fig. 3. The opposite end of the shell is provided with a shoul-

der 5 which forms a seat for a ring or washer 6, and beyond this shoulder the shell is projected at 7 and provided with an inturned lip or flange 8, thus forming a double shoulder. Within the recess between the shoulder 5 and flange 8 is arranged a piece or plate of glass 9, and this glass is held in contact with the ring 6 by means of a split spring ring 10 which is sprung in under the flange 8, and thereby firmly holds the glass in place. The glass may be replaced by any other transparent material or by a translucent or an opaque material. The ring 10 is preferably wedge-shape in cross-section.

Another shell 11 of sufficiently larger diameter than shell 1 to telescope over it, constitutes the other member of the movement box, and this shell 11 likewise has an opening for the insertion of a transparent or other plate 15, similar to plate 9, and adjacent to said opening is a double shoulder 12 in which is seated an annular spring, said spring comprising a flange 13 resting upon the shoulder 12, and the inwardly projecting or convergent spring-fingers 14. Upon the flange 13 is arranged the piece or plate 15, of glass or other material, and this plate is held in place by means of a split spring ring 16 also preferably wedge-shape in cross-section, sprung into place beneath an inturned lip or flange 17 at the upper edge of the shell 11.

As will be observed, between the shoulder 12 and the lip or flange 17 is a recess, as in the case of the shell 1, for the reception of the plate 15 and the ring 16. It is to be observed that the spring 13, 14, does not support the plate 15, but on the contrary, the shoulder 12 of the shell 11 supports both the spring and the plate. Next to and below the spring-fingers 14 is a ring 18 which is supported loosely upon any suitable projection 19, such as indentations, extending inwardly from the shell 11, and this ring 18 rests upon the dial or upper part of the projecting portion or plate or other member 3 of the watch movement. The ring 18 and spring-fingers 14, constitute a cushion for yieldingly holding the watch movement in position on its seat on the flange 2 in such way that while the movement is held rigidly under ordinary circumstances, its cushion will yield under extraordinary circumstances.

The two shells are connected, when tele-

scoped together, by means of bayonet joints 20.

The double shoulder on each end of the box serves as a set edge for the inserted plate 5 and keeps it from lateral motion; and it also allows space for the wedging action of the spring-ring to overlap the plate, and to take care of variation in thickness of the plates.

The ring or washer 6 affords a perfect seat 10 for the plate and makes the joint more nearly dust proof.

The casing comprises two telescopic members, one of them 21, having riveted or otherwise fastened in its bottom a spider-like 15 plate 22, the alternate arms 23 having the upwardly projecting spring-fingers 24 which are adapted to grip the projecting portion 7 of the movement box with sufficient firmness to hold the movement box against accidental 20 displacement when the cover of the box is removed, and to prevent the jarring of the movement box against inner sides of casing, and the other arms 25 being bent up in the bottom of the casing so as to constitute 25 springs to press the movement box upwardly and into engagement with the spring-fingers 24. The other member 26 of the casing has fixed in it a spider-like spring 27 whose ends 30 are slightly bent, as shown more particularly in Fig. 6, so as to grasp the upper member of the movement box. The two casing members are also provided with means for connecting them, such as three, more or less, bayonet joints, the lug-member 29 of which 35 is shown in Fig. 7, and the groove-member 30 of which is shown in Fig. 8.

When the movement box is assembled in its casing, and the casing members are locked together by their bayonet joints or other connecting means, the springs in the two members 40 of the casing exert sufficient pressure upon the top and bottom of the movement box to hold it in position and prevent its dislocation and also to take up shocks. These springs also 45 serve to center the movement box within the casing. This casing, however, is not herein claimed, but is reserved for a companion case of even date herewith, and any other form of casing may be used to receive the watch 50 movement box.

What we claim is:—

1. A watch movement box, having removable end plates, inner shoulders on the ends of the box to receive and support said plates,

outer shoulders beyond the inner shoulders 55 and having overhanging flanges, and spring rings of wedge-shape in cross-section sprung in beneath the flanges and above the plates.

2. In a box for watch movements, a shell having a shoulder, a ring or washer arranged 60 on said shoulder, a plate of glass or other suitable material on said ring, a spring ring of wedge-shape in cross-section placed outside of the plate and upon it, and an inturned flange on the shell engaging the spring ring. 65

3. In a box for watch movements, a shell having an inner shoulder, a ring arranged on said shoulder, a plate of glass or other suitable material on said ring, a spring ring of wedge-shape in cross-section placed outside 70 of the plate and upon it, an outside shoulder next to the inner shoulder and having an in-turned flange for engaging the spring ring, a movement-supporting flange on the other end of said shell, and a cover. 75

4. In a box for watch movements, a shell having a shouldered outer end, a ring having spring-fingers arranged and supported upon the shouldered portion of the shell, a plate of glass or other suitable material supported 80 upon the spring-finger ring, and a ring engaging the shell to secure the plate in place.

5. In a box for watch movements, a shell on which the movement is supported, and a cover for said shell having a loose ring, projections on the cover to support said ring, a spring bearing upon the opposite side of said ring, and means to hold the spring in place in the cover. 85

6. A watch movement box, having an 90 opening for the insertion of a transparent plate, a double shoulder seat in said opening for said plate having an inwardly projecting flange near the outer end of the box, and a spring ring of wedge shape in cross-section 95 adapted to be inserted through said opening and sprung in between the plate and flange to engage said flange and to overlap and clamp the plate against said seat.

In testimony whereof we have hereunto 100 set our hands this 25th day of May A. D. 1906.

JOHN H. GOSS.
ADRIAN F. WOLFF.

Witnesses:

J. H. PILLING,
HENRY FELL.

It is hereby certified that in Letters Patent No. 853,236, granted May 14, 1907, upon the application of John H. Goss and Adrian F. Wolff, of Waterbury, Connecticut, for an improvement in "Boxes for Watch-Movements," an error appears in the printed specification requiring correction, as follows: In lines 50-52, page 1, the words "has an opening for the insertion of a transparent or other plate, and" should be stricken out and inserted after the word "shell" in line 53, same page; and that the said Letters Patent should be read with this correction therein that the same may conform to the record of the case in the Patent Office.

Signed and sealed this 9th day of July, A. D., 1907.

[SEAL.]

E. B. MOORE,
Commissioner of Patents.
